CYLINDER HEAD ATTACHMENT

Roland Chilton, Ridgewood, and Rudolph F. Gagg, Fair Lawn, N. J., assignors, by mesne assignments, to Wright Aeronautical Corporation, Paterson, N. J., a corporation of New York

Application March 17, 1936, Serial No. 69,290

4 Claims. (Cl. 285—55)

This invention relates to the attachment of cylinder heads to cylinder barrels, and particularly comprises improvements in the screw thread type of joint now in use in air-cooled aircraft engines.

The conventional construction comprises an aluminum head screwed onto a steel barrel and many failures in the aluminum are caused by fatigue cracks engendered by the stress concentration which occurs at the sharp corners of the threads.

To overcome this difficulty it has been sought to use forged rather than cast aluminum alloys for the heads, but this involves a great increase in fabrication cost, in view of the excessive amount of machining required in producing the required finning from solid forgings.

The prime object of the present invention is to eliminate from the stressed portion of the head material the stress concentrations due to the threads, and thus to increase the strength and fatigue resistance of the structure.

The drawing is a fragmentary axial section through a cylinder head embodying the invention. In this drawing the head comprises the lower portion 10 equipped with the valve seats 12 and fins, shown as to their boundaries only, by the dotted lines 14. A conventional cylinder barrel 16 has screw threads 18 and fins 20 thereon. According to the provisions of this invention, instead of forming the companion threads in the material of the head 10, an annular recess having a very large radius or fillet 22 is provided and into this recess there is expanded, as by rolling, a ring 24 preferably of forged aluminum material. After the ring 24 is expanded into the head 10, the bore of the ring is threaded. Thereupon, the cylinder head, with the ring 24, is brought to an elevated temperature and is assembled to the steel barrel 16, the threads of the ring 24 engaging the threads 18 of the barrel 16, and the smooth bore of the head itself engaging the smooth surface of the cylinder below the threads.

It will now be seen that all sharp corners have been removed from the material of the head 10 and the large radius 22 substituted; this comprising the abutment between the head and the ring 24 by which the explosion forces to which the head is subject are resisted. It will also be seen that in this construction the ring 24 may be made of forged material, and further, that the loads between threads 18 and the curved abutment shoulder 22 are compressive and so do not tend to produce the tension fatigue cracks which have been experienced when these threads have been formed directly in the cast material of the head.

While we have described our invention in detail in its present preferred embodiment, it will be obvious to those skilled in the art, after understanding our invention, that various changes and modifications may be made therein without departing from the spirit or scope thereof. We aim in the appended claims to cover all such modifications and changes.

What is claimed is:

1. In a joint, an integral outer head member of material of low strength and fatigue resistance, said member having a cylindrical recess, an inner cylinder member engaging within said recess and extending therefrom, the recess having an annular groove, and a high strength and fatigue resistant ring in screw threaded engagement with said cylindrical member and engaging within said groove, whereby tensile stress between respective members is carried through said ring. 10

2. In apparatus of the class described, an integral head member having a cylindrical sided recess and an annular groove therein, said groove having an arcuate profile, a ring of material stronger than the member filling said groove and having threads formed in its recess, and a cylinder smoothly engaging within said recess having threads engaging the threads of said ring. 20

3. In a joint, a light alloy integral head member having a recess and an annular groove within the recess, a ring of material stronger than the member within said groove and in contact with the groove surface, said ring having screw threads formed on the bore thereof, and an externally threaded member screwed into said ring and smoothly engaging the surface of said recess. 30

4. In a joint between an annular integral head member and a tube member, the head member being of relatively weak material of such a character as not to have adequate strength for screw threaded engagement with the tube member, 40 said head member having a smooth cylindrical recess and an annular groove of arcuate profile in the cylindrical part of the recess, a strong ring capable of supporting screw threads, and having same in its bore, disposed within said groove and in bearing engagement with the surface thereof, said tube member smoothly engaging said bore and having external threads in screw engagement with threads of said ring, whereby relative tensile stress between said head and tube members is resisted by the strong ring compressively bearing on the surface of the head member groove and by the screw threaded connection between the tube and ring. 45
